UNITED STATES PATENT OFFICE

WILLIAM J. DUVALL, OF ST. LOUIS, MISSOURI, ASSIGNOR TO SMITH & DAVIS MANUFACTURING COMPANY, OF ST. LOUIS, MISSOURI, A CORPORATION OF MISSOURI

FOLDING BED

Application filed August 6, 1928. Serial No. 297,647.

This invention pertains to beds, and more particularly to improvements in portable folding beds of the "roll-away" type.

One of the objects of this invention is to provide an improved bed of the folding type, which, when extended, will have the appearance of an ordinary bed.

Another object of this invention is to provide such a bed which, when extended, will be securely locked in extended position.

Another object is to provide a folding bed of the type specified which will be secure against accidental collapse of the head frame upon the bed.

Another object is to provide such a bed which may be easily rolled, when in collapsed position, through narrow passages and into cramped spaces.

Another object is to provide improved means for supporting the bedding when the bed is folded up.

Further objects will appear from the following description, taken in connection with the accompanying drawings, in which—

Figure 1 is a perspective view, illustrating a bed embodying this invention in folded position;

Figure 2 is a view of the same in extended position;

Figure 3 is a detail of the latching device; and

Figure 4 is a detail of the bedding clamp.

Referring to the drawings, 1 designates a head frame, which may be of any usual construction, preferably of metal. Securely attached to the lower part of the head frame 1 is a sub-frame 2 extending forwardly from the head frame. This assembled combination is mounted on casters 3, so as to provide a portable bed of the so-called "roll-away" type.

This type of bed is intended to roll easily on its casters when in folded position. It has been found that when four casters are located at the four corners of a rectangle, there is a tendency for each pair of casters to set in parallel directions so that the bed tends to roll in straight lines and is not easily turned or guided along curved paths. In accordance with the present invention, the forward

casters are off-set inwardly with respect to the rear pair. When so placed, all the casters turn easily in any direction and the bed may be easily rolled and turned. This makes it easy to roll the bed through narrow doorways and into cramped spaces, such as a small closet, without danger of striking the walls.

The sub-frame 2 is provided with upstanding brackets 4, to which is pivoted at 5 a bed frame 6 of the usual type. The pivots 5 are arranged so that the bed frame 6 is outside the brackets 4 and the sub-frame 2. By this arrangement, when the bed is extended and made up, the side rails of the bed frame are aligned with the standards of the head and foot frames, and the sub-frame 2 is practically hidden, so that the bed has the appearance of an ordinary straight bed.

Pivoted on brackets 7 on the side bars of the bed frame 6 are links 8 and 9. The opposite ends of these links are pivoted at 10 and 11, respectively, to a foot frame 12. Pivoted at 13 to each link 9 is a link 14, whose other end is pivoted at 15 to the forward part of the subframe 2.

By this arrangement, the bed may be folded up by raising the foot frame 12, which causes the bed frame 6 to pivot at 5 on the sub-frame. During the upward movement, the links 9 are drawn downwardly by the links 14, so as to draw the foot frame 12 downwardly. By the time the bed frame 6 has reached a vertical position, the links 8 and 9 have moved to a position along the side bars, and the foot frame 12 is also folded against the bottom of the bed frame 6. A series of springs 16 connecting the rear end of the bed frame 6 with the forward extending portions of the sub-frame 2 counter-balance the weight of the bed and assist in raising the same. A weight 25 counter-balances the weight of the bed during the folding movement.

In the folded position, the links 9 and 14 form a toggle which locks the bed in folded position. The bed cannot be lowered by pulling forwardly on the bed frame, while a light pull on the foot frame will break the toggle and permit the bed to be lowered.

Mounted at the foot end of the bed frame

6 is a dog 17, which extends laterally slightly beyond the sides of the frame. One link 8 has pivoted thereto at 18 a latch 19 tensioned by a spring 20. As the bed is lowered to extended position, the dog 17 engages the upper beveled face of the latch 19, moving the same back so that, when the final position is reached, the latch will snap into locking engagement with the dog to secure the bed in extended position.

In order to support the bedding when the bed is raised to folded position, a pair of bedding clamps is mounted at the foot of the bed frame 6. One of these clamps is shown in detail in Figure 4 and comprises an arm 30 pivoted at 31 on the bed frame 6. At the upper end of the arm is mounted a finger 32 having a curled end 33 adapted to engage the bedding. The finger 32 is pivotally mounted in a tubular bearing 34 on the end of the arm 30. The finger is free to rotate in the bearing 34, except as limited by the off-set portion 35 of the finger. This arrangement permits the finger to be turned in its bearing 34, so as to be disengaged from the bedding and be out of the way during the normal use of the bed. When it is desired to clamp the bedding, the finger is turned to the position illustrated in Figure 4, its further rotation being prevented by the off-set portion 35. The arm 30 is then swung downwardly to the left (Fig. 4) on its pivot 31, so as to bring the finger 32 down upon the bedding to clamp the same. The arm 30 is held in clamping position by a pawl 36, which engages in the teeth of a straight ratchet 37 mounted on the bed frame 6. These bedding clamps are not a part of the present invention, but are described in Patent No. 1,624,222.

Pivoted at 38 at the head of the frame 6 is a bedding holder 39. This is arranged to rest in upright position as shown in Figure 2, when the bed is extended. When the bed is folded, however, the holder 39 comes into engagement with the rear cross-bar of the sub-frame 2, as illustrated in Figure 1. This action moves the holder 39 upwardly so as to bring the same into supporting engagement with the bedding at the end thereof so as to assist in supporting the same. This arrangement prevents the bedding from sagging below the end of the bed frame, so as to come into contact with the sub-frame or to drag on the floor. The bedding clamps 30 at the foot of the bed securely hold the bedding to the bed frame, and the holder 39 reduces any tendency of the bedding to sag below the lower end of the bed frame. Thus, the bedding is protected against accidental soiling.

When the bed is extended and latched, the forward part of the sub-frame is tied to the foot of the bed frame through the links 14, 9, 8, the foot frame 12 and the latch 19. Accordingly, accidental collapse of the bed by

pushing forwardly on the head frame 1 is impossible.

It will be seen that this invention provides a folding bed of the "roll-away" type, which, when extended, has the appearance of an ordinary bed. The arrangement of the pivots 5 with the brackets 4 inside the frame 6, renders the sub-frame inconspicuous, so as to be easily hidden when the bed is made up. The latches 19 secure the bed in extended position, so as to prevent its folding up accidentally. These latches are manually disengaged when the bed is to be folded up.

While this bed has been described as a unitary structure, it is obvious that certain features may be used to advantage without others, and the use of such sub-combinations is contemplated by this invention.

It is further obvious that various changes may be made, within the scope of the appended claims, in the details of construction, without departing from the spirit of this invention. It is, therefore, to be understood that this invention is not to be limited to the specific details shown and described.

Having thus described the invention, what is claimed is:

In a folding bed, a sub-frame, a bed frame, pivotally mounted on the sub-frame, a foot frame, a link connecting said foot frame to said bed frame, a latch on the link disposed to engage said bed frame, and maintain said foot frame in extended position, a second link connecting said bed frame and foot frame, said links cooperating to guide and brace the foot frame in its movements, and an operating member connecting said second link to said sub-frame.

In testimony whereof I affix my signature this 26th day of July, 1928.

WILLIAM J. DUVALL.
